LABELING MACHINE

Hans A. Nefzger, Hackensack, N. J., assignor to
 New Jersey Machine Corporation, Hoboken,
 N. J., a corporation of New Jersey

Application November 6, 1943, Serial No. 509,167

4 Claims. (Cl. 216—56)

The invention relates to labeling machines and more particularly to labeling machines of the type disclosed in the von Hofe United States Patent No. 2,227,816 of January 7, 1941.

Labeling machines of the type indicated are designed for labeling articles of varying classes and dimensions and are adapted for applying labels to small articles as exemplified by conventional ampules. The latter being relatively small and of comparatively little weight are easily disturbed, when in label-receiving position, for instance by vibration developed in the machine during an operative period and by other forces. As a result, labeling of such ampules and other small articles is rather haphazard and unsatisfactory with resultant loss in time and materials.

The object of the invention is to provide a novel supporting means for the articles to be labeled whereby the above objections will be overcome and whereby the ampules and other small articles will be firmly maintained in accurate label-receiving position regardless of vibration or other disturbing forces.

Other objects will appear from the description hereinafter and the features of novelty will be pointed out in the claims.

In the accompanying drawings, which illustrate an example of the invention without defining its limits,

Fig. 1 is a perspective view of the novel support in dual form;

Fig. 2 is a cross-section of the support, and

Fig. 3 is a diagrammatic view illustrating an example of label-applying mechanism adapted for co-operation with the novel support.

The novel support comprises a block 10 of rectangular cross-section provided with longitudinal flanges 11 in spaced parallel relation to form a channelled upper surface as shown in Fig. 2. A supporting member 12 has its base portion fitted between the flanges 11 and rests upon the bottom of the channel formed thereby. The member 12 preferably converges upwardly and terminates in a seat 13 which may be curved as shown or otherwise shaped to conform to the shape of the articles to be accommodated thereby. In the illustrated example the seat 13 is designed to support articles 14 of circular or curved cross-section such as ampules and the like.

The block 10 is provided with an interior chamber 15 communicating with a nozzle 16 secured in place, for instance, by being threaded into the block 10 as illustrated in Fig. 2. The nozzle 16 serves to receive the end of a flexible tube 17 whereby the chamber 15 is connected with a vac-

uum pump or other means for developing suction therein.

The chamber 15 is provided with one or more preferably reduced vents 18 which terminate at the bottom of the channel formed by the flanges 11. In the assembled condition, the vents 18 register with channels 19 formed in the supporting member 12 and terminating at their outer ends at the seat 13 thereof.

5 The member 12 is so mounted between the flanges 11 that the connections between the respective vents 18 and the respective channels 19 will be substantially air-tight. To enable supporting members 12 of different types and dimensions to be used, the mounting thereof on the block 10 may be of a removable type. As shown, one or more set screws may be provided for fixing the member 12 in place on the block 10.

10 As shown, the novel supporting means is carried by a base-plate 21 which in turn is secured upon a suitable upright bracket 22 arranged and located in the labeling machine in any convenient manner at the label-applying station thereof.

15 Preferably, the block 10 is resiliently supported on the base-plate 21 so as to yield during the application of the labels to the articles 14 to thereby avoid fracture of or injury to the latter.

20 In the illustrated example the block 10 is provided in its lower face with recesses 23 for the accommodation of springs 24 which bear against the base plate 21 and permit the block 10 and its associated elements to yield as the labels are applied to the articles 14. The block 10 is maintained in place on the base plate 21 and guided 25 in its vertical movements by angle members 25 which are provided with slots 26 in which pins 27 carried by the block 10 are slidable.

25 As shown in Fig. 1, a plurality of supporting devices may be mounted on a common base-plate 21 with the latter carried by the bracket 22, it being understood that the multiple supporting means is located in the labeling machine at the label-applying point or station thereof. In any case, whether the novel supporting means is of 30 the multiple type or comprises a single unit it may be embodied in many different types of labeling machines and is particularly adapted for incorporation in labeling machines of the type disclosed in the von Hofe patent previously mentioned herein.

35 As diagrammatically illustrated in Fig. 3, the labels 28 are located in a suitable container 29 in the form of an upright stack at what may be conveniently termed the label pick-up station 40 of the machine. Suitable provision may be made

in any conventional manner to adjust the stack upwardly for the purpose of periodically restoring the upper end of the stack to a predetermined level, for instance, as shown in the von Hofe Patent No. 2,227,816.

The labels 28 are removed in individual succession from the upper end of the stack by means of a suction head 30 which is supported by and vertically-adjustable upon a carriage 31. The latter is arranged to be reciprocated on a stationary rail 32 by suitable mechanism exemplified by the rod 33 and shown in detail in my patent hereinbefore mentioned, to carry each successive label 28 from the stack to the point of application or label-applying station at which the article 14 is supported in the seat 13 of the supporting member 12.

It will be understood that the article 14 which may be an ampule or other relatively small article is maintained in position in the seat 13 by the suction in the channel or channels 19 and chamber 15 by reason of the connection of the latter with a source of suction through the medium of the nozzle 16 and tube 17.

In the operation of the mechanism, the suction head 30 is lowered at one terminus of the reciprocation of the carriage 31 to pick up a label 28 from the stack and then raised and shifted with the carriage 31 along the rail 32 to the aforesaid point of application. At this point the suction head 30 is lowered to apply the label 28 carried thereby to the ampule or other article which is held in label-receiving position in the seat 13 by the suction effective thereof. It will be understood that the suction effective at the active surface of the suction head 30 is controlled in any conventional manner, for instance, as disclosed in the von Hofe Patent No. 2,227,816, in proper synchronism with the aforesaid operative steps to produce the desired results.

During its travel from the stack to the point of application, the label 28, carried by the suction head 30, receives a coating of adhesive, for instance, by being passed in tangential engagement with a suitably mounted adhesive-applying roller 34. It will be understood that in the return direction the suction head 30 travels at a level above the adhesive-applying roller 34 so as not to be soiled by adhesive therefrom. After the label 28, carried by the suction head 30 has been applied to the ampule, or other article 14, and left in initial adhesive contact therewith by the elevation of the suction head 30, the application of said label to said ampule 14, or other article, may be completed in any convenient manner, for instance, as illustrated and described in the previously mentioned von Hofe patent.

During all of these operations the ampule 14, or other article, is securely held in label-receiving position in the seat 13 by the suction effective thereof. As a result the ampule 14, or other article, is incapable of being unintentionally shifted by the vibration of the mechanical parts or by any other forces which may be developing during such operative period. When the application of the label to the ampule 14, or other article, takes place the supporting member 12 and block 10 with their associated elements yield downwardly against the compression of the springs 24 and thereby prevent the label-applying pressures from fracturing or otherwise injuring the ampule 14, or other article, in label-receiving position in the seat 13. When the

application of the label has been completed the labeled ampule 14, or other article, is removed from the seat 13 by simply exerting a removal force thereon sufficient to overcome the restraining effect of the suction developed at the seat 13. With this arrangement the developed suction is such as to hold the ampule 14, or other article, firmly in label-receiving position in the seat 13 and yet is not sufficiently strong to require excessive forces to be exerted on the ampule 14, or other article, to remove the same from the seat 13. If desired, provision may be made for instance in the form of a foot-pedal-controlled valve for controlling the suction effective in the channel or channels 19 so as to enable the suction to be relieved when it is desired to remove the labelled ampule 14, or other article, and to restore said suction at the seat 13 for the purpose of holding the succeeding ampule 14, or other article, in place therein.

It will be understood, if a plurality of the novel supporting devices are mounted upon a single base plate 21 as shown in Fig. 1, that two containers 29 for two stacks of labels 28 will be provided in the machine and that two properly co-operating suction heads 30 will be mounted on the carriage 31 so as to operate as a single unit in the manner previously described herein.

The novel supporting means is exceedingly simple in construction and enables small articles such as the ampules 14 to be efficiently labeled in an accurate manner and without requiring any particular care or supervision on the part of the operators.

By mounting the supporting member 12 on the block 10 in such a manner as to permit the easy removal of said supporting member 12 at will, it is possible to readily substitute different types of supporting members 12 as this may be required. It will be understood that to secure the best results the seat 13 of the supporting member 12 should always be such as to properly fit and support the articles to be labeled for which it is designed. The aforesaid interchange of supporting members 12 makes this result comparatively easy to attain.

Although the present invention has been described in conjunction with a preferred embodiment, it is to be understood that modifications and variations may be resorted to without departing from the spirit and scope of the invention as those skilled in the art will readily understand. Such variations and modifications are considered to be within the purview and scope of the claims.

I claim:

1. In a labeling machine, the combination of an upright bracket, a base-plate carried by said bracket, angle irons secured upon said base-plate and having upwardly-projecting members located in opposed spaced parallelism with each other, a vertically movable block mounted between said upwardly-projecting members and having a channeled upper surface, said block being provided with an interior chamber connected with a source of suction and having at least one relatively reduced vent terminating at said channeled upper surface, a supporting member terminating in a seat for the accommodation of articles to be labeled, said supporting member being removably secured in the channeled upper surface of said block and having at least one channel in communication with said reduced vent and opening at said seat whereby an article to be labeled will be maintained in

said seat, by suction, against unintentional shifting, and yielding means effective on said block to enable the latter to yield under label-applying pressure and thereby prevent the latter from injuring said article.

2. In a labeling machine, supporting means for supporting articles in label receiving position, comprising a movable block having an interior chamber connected with a source of suction and provided with at least one vent, an upright supporting member removably mounted on said block and terminating in a seat for the accommodation of articles to be labeled, said supporting member having at least one channel in communication with said vent and opening at said seat whereby an article to be labeled will be maintained in said seat, by suction, against unintentional shifting, and springs effective on said block to yieldingly oppose label-applying pressure on said article and thereby prevent said pressure from injuring the latter.

3. In a labeling machine, supporting means

for supporting articles in label-receiving position, comprising a movable block having an interior chamber connected with a source of suction, a supporting member projecting upwardly from said block and provided with a seat for the accommodation of articles to be labeled, said supporting member having at least one channel open at said seat and communicating with said chamber whereby suction in the latter is effective at said seat to maintain articles in place therein, and a spring effective on said movable block to yieldingly oppose label-applying pressures on said articles to prevent injury thereto.

4. In a labeling machine, supporting means provided with a seat for accommodating highly fragile articles to be labeled, means whereby suction is made effective at said seat for maintaining articles in place thereon, and yielding means effective on said supporting means to yieldingly oppose label-applying pressures on said articles to prevent injury thereto.
